UNITED STATES PATENT OFFICE.

HENRY THOMSON, OF PERTH, WESTERN AUSTRALIA, AND WILLIAM R. OYSTON, OF KENSINGTON, NEAR SYDNEY, NEW SOUTH WALES, AUSTRALIA; SAID OYSTON AS-SIGNOR TO SAID THOMSON.

PIANO PLAYER.

Application filed November 13, 1920. Serial No. 424,811.

To all whom it may concern:

Be it known that we, HENRY THOMSON, residing at Perth, in the State of Western Australia, Commonwealth of Australia, and 5 WILLIAM ROBERT OYSTON, residing at Kensington, near Sydney, in the State of New South Wales, Commonwealth of Australia, both subjects of the King of Great Britain, have invented new and useful Improvements in and relating to Piano Players, of 10 which the following is a specification.

This invention relates to improvements in piano-players and in particular to a piano-player of improved construction adapted to 15 be fitted to existing pianos without requiring the exercise of special technical skill for the purpose. Alternatively, player mechanism according to the invention may be built into pianos in the manufacture of player- 20 piano instruments.

It is an object of the invention to provide piano-player apparatus possessing great durability even under adverse climatic conditions and having working parts of such 25 construction, design and arrangement that they can be readily removed and replaced as conditions may require.

A further object of the invention is to provide a compact piano-player having a 30 reduced number of operating parts of simplified construction and the sets of parts for the various actions so constructed that in manufacture they are standardized and can be individually and carefully tested before 35 being placed into a complete assembly.

The invention provides an internal player apparatus having means whereby a vacuum is maintained in a main chamber which is 40 placed selectively into communication by means of control valves with collapsible pneumatics of improved construction arranged in a single row and operating, through transmission devices, the piano actions. The transmission devices are self-aligning and so constructed as to reduce 45 friction to a minimum, and they are further characterized by dispensing with the use of combination lever systems and pivot bearings of any nature.

50 Each set comprising an operating pneumatic casing for control valve and motion transmission device is of unitary construction, thereby facilitating manufacture of the player apparatus and assembly of its parts in correct operative positions.

The main vacuum chamber, the operating pneumatics, the control valves and the spool-box are so constructed and arranged that when fitted into a piano case they are all located above the hammer actions of the 60 instrument, thereby obviating the necessity of altering in any manner the construction or design of the piano actions to accommodate the player apparatus.

Bracket supporting means are also provided whereby the whole of the player operating apparatus can be readily placed into correct positions within the piano case and conveniently removed therefrom for inspection, testing or repair purposes. 65

The invention consists of the features of construction, combination and arrangement hereinafter fully described, reference being had to the accompanying drawings wherein:— 70

Figure 1 is a sectional elevation of the internal player apparatus illustrating its arrangement within a piano case.

Figure 2 is a side elevation of a supporting bracket and attached vacuum chamber— 80 the latter being in section.

Figure 3 is a view in front elevation of the supporting bracket.

Figure 4 is a sectional elevation of the vacuum chamber and its tubular end supporting bracket. 85

Figure 5 is a front view and Figure 6 is a view in plan of the tubular bracket supporting the end of the vacuum chamber casing shown in Figure 4. 90

Figure 6^a is a view in end elevation of the bracket for supporting the opposite end of the vacuum chamber casing.

Figures 7 and 8 are views in vertical section illustrating alternate pneumatic and 95 control valve units secured to the vacuum chamber.

Figure 9 is a view in plan of the pneumatic and valve casing unit.

Figure 10 is a view in perspective of the 100 control valve and its supporting diaphragm.

Figure 11 is a view in plan and Figure 12 is a rear elevation illustrating the pneumatics in single row arrangement and the 105 control valves thereof.

Figure 13 is a view in plan of a diaphragm cap seating and tracker tube coupling.

Figures 14 and 15 are perspective views 110 of part of the motion transmission devices.

- Figure 16 is a sectional view illustrating a pneumatic prior to action, and Figure 17 is a similar view illustrating the pneumatic in its active position.
- 5 Figure 16^a is a view in detail illustrating the lower portion of the transmission device out of action and in relation to the inactive pneumatic illustrated in Figure 16.
- 10 Figure 17^a is similar view of the transmission device in action and relatively to the collapsed or active pneumatic illustrated in Figure 17.
- 15 Figure 18 is a section elevation and Figure 19 is a plan of an abutment attachment to the wippines of the hammer actions.
- 20 Figure 20 is a view in detail showing a modified arrangement of mounting the abutment member for engagement by the transmission device.
- 25 In the drawings, 20 indicates a casing, preferably of wood, having a vacuum chamber 21 extending approximately the full length of the piano case. This casing is supported within the piano case above the hammer actions of the piano by means of a tubular bracket 22 (Figs. 4, 6 and 11) and by a solid bracket 29, (Fig. 6^a) said brackets being fitted to the opposite interior ends of the piano case by means of screws passed 30 through holes 25 formed in said brackets. The vacuum casing is secured to the brackets 22 and 29 by means of screwed studs 23 having milled heads 24 and passing through a strengthening rib formed in said vacuum chamber.
- 35 A recess 26 is formed on the inside face of the tubular bracket 22 and is in communication by means of a port 27 with the vacuum chamber 21. A tubular extension 40 or socket 28 extends downwardly from the recess 26 and it is connected by tubing 28^a to a vacuum motor (not shewn), the operation of which maintains a constant vacuum in said chamber 21 through the communications of tubing 28^a, extension 28, recess 26 in said tubular bracket and port 27 leading to said vacuum chamber.
- 45 The vacuum motor is preferably of the construction described in the specification 50 of our co-pending application for Letters Patent Serial No. 424,810.
- 55 On the vacuum casing 20 there is mounted a spool-box 30 having means for supporting a music-roll 31, a take-up spool 32 and a tracker-bar 33, and other equipment of standard or conventional construction. The spool propelling mechanism (not shewn) may be of known construction, and it is fitted in alignment with said spool-box.
- 60 Said spool-box and spool-propelling mechanism are positioned in the piano case above and in advance of the hammer actions as is clearly illustrated in Figure 1.
- 65 The vacuum casing 20 and its attachments are further supported at suitable points be-
- tween the end brackets 22 and 29 by means of intermediate brackets 34—see Figures 1, 2 and 3.
- 70 Ordinarily two of these intermediate brackets are employed, and each has at its upper end a flange 35 for attachment by means of screws 36 to the front wall of said casing 20. The lower end of each of said intermediate brackets is fixed by means of a screw 37 to a longitudinal rail 38 detachably fitted to the piano case, to which rail a key-lock 39 is hingedly attached. This key-lock extends approximately the full length of the piano and it is shod with a leather pad or felting strip 40. The function of said key-lock is to prevent the piano keys from following the upward movement of the wippines of the hammer actions when the latter are mechanically actuated. When said key-lock is raised to the position indicated by broken lines in Figure 1, the piano keyboard is free to be manually operated.
- 75 Operating pneumatics corresponding in number to the instrument keys are arranged in a single row in front of the vacuum casing 20 and above the hammer actions.
- 80 Each of these pneumatics has a top stationary plate 42 surmounting two floating plates 43 and 44, the intervening spaces between the plates of the pneumatic being enclosed by an envelope 45 of flexible material. This envelope is so folded or creased that upon the exhaust of air from the pneumatic, the envelope collapses inwardly, thus drawing the two floating plates towards the stationary plate of the pneumatic.
- 85 In order that the reciprocating actions of the pneumatics caused by the exhausting and replenishing of air can be repeated for long periods without causing rupture of the envelope, the latter is preferably formed from animal gut attached by means of glue or other adhesive to the said plates in two layers—one with the grain and one across the grain. These two layers of membrane are united as by means of a rubber solution.
- 90 An important feature of the construction of the pneumatics is that their width is less than one-half of their height when expanded, as is illustrated in Figures 16 and 17. Provision is thereby made in a small compass for a large displacement of air with a corresponding exertion of force and with a minimum of movement owing to a larger area of gut being exposed to the action of the air than is the case with an ordinarily constructed wide and low pneumatic having hinged members. Each of the top plates of the pneumatics is formed with a lug 46 having a slot 47 to receive the inwardly bent end 48 of a longitudinal angle plate 49.
- 95 Secured to the lower portion of said angle plate 49 are forked guides 50 furnished with felted linings 51.
- 100 The top plate 42 of the operating pneu-

matic is of cast metal, preferably aluminium, and it is formed integrally with the valve casing 52 being connected thereto by a throat in which is formed a passage 53. 5 The valve casing has a flange 54 for attachment to the vacuum casing 20, and it is constructed with an upper valve chamber 55 and a lower valve chamber 56, which chambers are divided by a wall 57 having a central orifice 58 forming a valve seating. 10

The upper valve chamber 55 has a detachable retaining cap 59 having an air inlet 60. Seated about the central orifice in the divisional wall 57 is a valve 61 having a stem 62 which extends into the lower valve chamber 56. Across this lower chamber there is secured a flexible diaphragm 63, the diameter of which exceeds that of said valve 61. 15 20 A cap seating 64 is detachably fastened to said valve casing below the diaphragm 63, and a recess 65 formed in said seating is disposed immediately under said diaphragm. An outlet passage 66 extending from said recess 65 communicates with a nipple 67 to which is connected a flexible tracker tube 68 leading from one of the air-ducts of the tracker-bar 33.

The lower chamber 56 in the valve casing 30 is connected by a slot or perforation in an exhaust passage 69 to the main vacuum chamber 21. A small vent or bleed hole 70 connects the passage 66 with the exhaust passage 69 leading to the main vacuum chamber 21 and a pin 71 is adjustably fitted into said vent for the purpose of regulating the area thereof.

This vent 70 is to enable the tracker tube 68 connected to the nipple 67 to be pneumatically exhausted. A slight suction is thus created in the tracker tube sufficient to exhaust the air therefrom when covered by the music-sheet and prevent the operation of the valve 61, but insufficient to exhaust it when uncovered by the music-sheet. This suction serves to retain the music-sheet in close contact with the tracker-bar 33 in the operation of the piano-player apparatus.

The suction exerted on the underside of the valve 61 ensures the latter being firmly seated, but when a slot in the travelling music-sheet registers with a duct in the tracker-bar 33 an influx of air takes place and enters the recess 65 beneath the flexible diaphragm 63.

The diaphragm has an area greater than that of the underside of the valve 61, and in consequence the pressure of air, so admitted, immediately overcomes the atmospheric pressure on the valve which is raised, motion being communicated thereto through the valve stem 62. When the valve is raised from its seat it closes the air inlet 60, and the contained air of the pneumatic 41 is

exhausted through the passage 53, valve seat 58 orifice 58 and passage 59, the latter communicating with the vacuum chamber 21.

Upon the exhaust of air from the pneumatic, the envelope thereof collapses inwardly thus drawing the two floating plates 43 and 44 upwardly.

Special features of the internal piano-player according to the invention reside in the employment of operating pneumatics arranged in a single row: in the unitary construction of pneumatic, valve casing and motion transmission device: and in the construction of motion transmission device which is direct acting and is characterized by the absence of lever actions and pivot 75 80 bearings.

The valve casings 52 having of necessity a greater diameter than the width of the improved construction of pneumatic are arranged in two series in longitudinal alignment, but with one series of alternate valve-casings at a higher plane than the other series of intermediately positioned valve-casings. Each of the combined pneumatic and valve-casing units of the lower series 85 90 is constructed as illustrated in Figure 7, and each of such units of the upper series is constructed as illustrated in Figure 8. The throats having passages 53 which extend from the top stationary plates 95 of alternate pneumatics are of less height and are arranged at a more acute angle than the corresponding throats extending from the top plates of the other series of pneumatics, and the air exhaust passages 69 of one series 100 of valve-casings communicate with the upper portion of the main common vacuum chamber, while the corresponding exhaust passages of the lower positioned series of valve casings communicate with said vacuum chamber at relatively lower points. Furthermore, the cap seatings 64 of the higher positioned series of valve-casings have their nipples 67 for connection to the tracker tubes arranged vertically, or approximately 105 110 so, while the nipples of the alternating series are downwardly inclined from the passages 66 of their cap seatings 64.

The upward motion of the floating plates 43 and 44 in the collapsing action of the pneumatic is transmitted by means of a vertical pull-rod or wire 72 to the wippen 73 of a hammer action. The upper end of said pull-rod 72 is threaded and is secured into the bottom floating plate 44 of the pneumatic. This bottom floating plate of the pneumatic may, for purposes of special durability, be constructed of two layers of wood of desired thickness secured together by an adhesive, the grain of the wood in one layer being opposed to the grain of the wood of the other layer to prevent warping.

The pull-rod 72 extends downwardly from

its pneumatic passing freely through the felted guide 50 and at a lower position through a guide 74 which latter is rigidly secured to the rail 38.

5 A tappet or arm 75 is adjustably mounted by means of a set-screw 76 on the lower end of said pull-rod, and is positioned thereon so as to actuate hammer action by raising an abutment button 77 of peculiar construction affixed to the free end of the wippen 73.

In the modified arrangement illustrated by Figure 20 said abutment button is fitted above the wippen by being secured to a small bracket 73^a on the tension tape supporting wire 73^b.

10 In this construction the tappet or arm 75 is correspondingly raised on the pull rod 72 to contact with the underside of said button, and without interfering with the arrangement of the hammer actions to permit manual operation of the instrument in the ordinary manner.

15 The abutment button 77 is characterized by having two parallel members flexibly connected together, and in the construction illustrated it comprises an eye-screw 78 screwing into the end of the wippen, top and bottom washers 79 and 80 fitted to said eye-screw by a bolt 81, and a narrow strip 82 of leather or other flexible material secured to the underside of the lower washer 80 and to the upper side of a button 83 of wood shod with a fitting pad 84. The connection of the two button members by a flexible strip permits the lower member 83 to oscillate slightly, whereby the friction between the adjustable tappet 75 and said abutment button is reduced to a minimum in the transmission of motion from the operating pneumatic to the hammer action.

20 The guide 74 on the rail 38 is provided with an adjustable check screw 85, and in vertical alignment therewith is a buffer 86 secured to the upper side and at the rear end 45 of the tappet 75, which buffer is adapted in the upward movement of said tappet to contact with the head of said check screw.

25 An adjustment of said check-screw regulates the distance between the head thereof and said buffer pad, thereby limiting to a predetermined degree the upward stroke of the pull-rod 72 and consequently the movements of the floating plates 43 and 44 in the collapsing action of the pneumatic. This 35 feature of construction is clearly illustrated in detail by Figures 16 and 16^a, and Figures 17 and 17^a.

30 Secured to the interior of the piano case are small blocks 87 positioned immediately below the lower ends of the intermediate supporting brackets 34. Each of these blocks has a groove or recess 88 on its upper surface, lined with felt or other soft material, to receive the curved lower end of said

35 bracket 34 when dismantling the player actions, thereby functioning as resilient pivots to facilitate the removal of said actions as a complete unit from the piano case.

40 In the assembly of the player apparatus, the player actions, each set of which comprises an operating pneumatic 41, valve casing 52, air passage throat 53 and motion transmitting rod 72 in unitary construction, are fitted to the front wall of the vacuum casing 20, a screw being used for each unit. 75

45 The intermediate supporting brackets 34 are secured at their upper ends to said vacuum casing and at the lower ends to the rail 38. The spool-box and spool-motor casing (with their contained mechanisms) 80 are fitted to said vacuum casing above the single row of pneumatics when the tracker tubes 68 leading from the air-ducts of the tracker-bar are connected to the nipples 67.

50 The vacuum casing with its attachments is 85 then detachably fitted to the brackets 22 and 29 secured to the piano case in the manner described.

55 By releasing the two studs 23 on the end brackets 22 and 29, and by releasing the 90 rail 38 from the piano case, the vacuum casing, spool-box and motor, and all of the player actions can be removed bodily as one unit from the piano-case.

60 What we do claim is:— 95

1. In piano-player apparatus, an operating pneumatic having a stationary plate, two floating plates and an envelope of flexible material affixed to said plates and arranged to collapse upon the exhaust of 100 air and thereby draw the floating plates towards the stationary plate, the width of the pneumatic being not more than one-half of its height when expanded.

65 2. In piano-player apparatus, an operating pneumatic having a stationary plate, two floating plates and an envelope of flexible material affixed to said plates in two layers—one with the grain and the other across the grain, the width of the pneumatic being not more than one-half of its height when expanded. 110

70 3. In piano player apparatus, an operating pneumatic having a stationary plate, two floating plates disposed at one side of the 115 stationary plate and an envelope of flexible material for said plates, said envelope being attached to the stationary plate and carrying the floating plates and arranged to collapse upon the exhaust of air and draw the floating plates toward the stationary plates, a rod secured to a floating plate of said pneumatic, and means carried by said rod to operatively connect the rod to and actuate the wippen of the piano action by the movement of said rod caused by the collapsing of the pneumatic. 120

75 4. In piano-player apparatus, a series of 125

1. pneumatics arranged in a single longitudinal row in parallel relation, each of said pneumatics having a rod secured thereto, and means to operatively connect the rod 5 to and actuate the wippen of the piano action by the movement of said rod caused by the collapse of the pneumatic to engage and actuate a hammer action of the instrument.
10. 5. In piano-player apparatus, an abutment through which a hammer action of a piano is actuated, comprising two button members flexibly connected together and permitting oscillatory movement of one 15 member relative to the other member, and means for attaching said abutment to the hammer action.
6. In piano-player apparatus, an abutment through which a hammer action is actuated, comprising an eye-screw, washers fitted to opposite sides of the eye, said screw, and a button shod with soft material flexibly connected to one of said washers.
7. In piano-player apparatus, an unitary 25 construction of operating pneumatic having a stationary plate and two floating plates arranged at one side of the stationary plate, and control-valve casing integral with said stationary plate, and a motion transmission 30 device fixed to the outer floating plate of said pneumatic.
8. In piano-player apparatus, a unitary construction of operating pneumatics including a stationary plate and a pair of floating 35 plates arranged at one side of the fixed plate, control-valve casings integral with the stationary plates of the pneumatics and motion transmission devices secured to the floating plates of said pneumatics, said pneumatics 40 being arranged in parallel relation in a single longitudinal row.
9. In piano-player apparatus, an operating pneumatic having a stationary plate, two floating plates, an envelope fixed to said 45 plates and folded to collapse inwardly, a valve casing, a throat integral with the stationary plate of the pneumatic and valve casing and in communication with said valve casing and with said pneumatic through a 50 port in the stationary plate of the pneumatic, and a motion transmission device fixed to the outermost floating plate of said pneumatic.
10. In piano player apparatus, a chest 55 having a main vacuum tank, means for supporting said chest in a piano case above the hammer actions, pneumatic control valve casings mounted in a longitudinal row on said chest having exhaust passages in communication with said vacuum chamber, operating pneumatics, throats projecting laterally from the casings and having an extended member to constitute a fixed part of the pneumatics with the passages therin connecting said casing with their respective 60 pneumatics, and means to operatively connect the pneumatics with the hammer actions of the piano.
11. In piano-player apparatus, a chest having a main vacuum chamber, a tubular 70 bracket for supporting said chest, having a port communicating with said vacuum chamber, a tubular extension on said bracket, and piping leading from an exhaust motor and connected to said extension. 75
12. In piano-player apparatus, a chest having a main vacuum chamber, brackets fitted to the interior ends of the piano-case and supporting said chest above the hammer actions, a rail secured to the piano case, 80 brackets fitted at their upper ends to said chest intermediate of said end brackets and secured at their lower ends to said rail, guides for said intermediate brackets, and a pipe connection from an exhaust motor to 85 said vacuum chamber through one of said end supporting brackets.
13. In piano player apparatus, a chest having a vacuum chamber supported within the piano case above the hammer action, 90 pneumatic control valve casings arranged in two substantially parallel series, one at a higher level than the other, upon the chest in communication with the vacuum chamber, operating pneumatics arranged in a single 95 row in parallel relation, throats projecting laterally from the valve casings and having an extension forming a fixed part of the pneumatics, the passages through said throats leading from said casings to said 100 pneumatics, said pneumatics, throats and valve casings being of a unitary structure, and rods secured to said pneumatics for the purpose specified.
14. In piano player apparatus, a pneumatic comprising a fixed plate, a pair of floating plates substantially parallel with and at one side of the fixed plate, a flexible envelope for said plates and attached to the fixed plate, said envelope being so creased as to collapse upon the exhaust of the air from the envelope and draw the floating plates towards the fixed plate, and an actuator secured to the outermost floating plate. 105
15. In piano player apparatus, a pneumatic control valve casing having an exhaust valve and arranged for connection to a vacuum chamber, and having an integral throat piece with the passage therein in communication with the valve casing, and said throat piece having an extended portion to serve as a fixed part of a pneumatic. 115
16. In piano player apparatus, a chest to extend longitudinally of the piano and having a vacuum chamber extending longitudinally thereof; brackets to support said chest, one of said brackets being hollow and in communication with the vacuum chamber and arranged for connection to vacuum creating means; pneumatic control valve 120 125 130

casings connected to said chest in communication with the vacuum chamber; and actuating pneumatics carried by and in communication with the valve casings and arranged in a longitudinal row in parallel relation to each other.

17. In piano player apparatus, an operating pneumatic having a fixed plate, floating plates arranged at one side of and in parallel relation with the fixed plate, and a flexible envelope extending about said plates and attached to said plates and arranged to collapse upon the exhaust of air therefrom and draw the floating plates toward the fixed plate.

18. In piano player apparatus, a vacuum chamber, a pneumatic control valve casing in communication with said vacuum chamber, an operating pneumatic in communication with the valve casing; a rod secured to said pneumatic; a tappet adjustably mounted on the rod; and an abutment attached to the wippen of the hammer action of the piano to be engaged by the tappet to actuate said hammer action by the movement of the rod caused by the collapse of the pneumatic.

19. In piano player apparatus, a vacuum chamber; pneumatic control valve casings in communication with said vacuum chamber; operating pneumatics in communication with said valve casings arranged in a longitudinal row in parallel relation; a rod secured to each of said pneumatics; guides for said rods; abutments attached to the wippen of the hammer actions; tappets adjustably mounted on the rods to engage said abutments by the movement of the rods caused by the collapsing of the pneumatics to actuate the hammer actions; and means for limiting the movement of said rods.

20. In piano player apparatus, a chest having a vacuum chamber; brackets for supporting said chest in the piano casing; pneumatic control valve casings mounted on said chest in communication with the vacuum chamber; pneumatics carried by said casings in communication therewith and arranged in parallel relation in a horizontal row; rods secured to said pneumatics arranged with means to actuate the hammer actions of the piano, said vacuum chest, valve casings and pneumatics being of unitary construction whereby the same may be mounted in and removed from a piano case as a unit.

21. In piano player apparatus, a valve casing having a laterally projecting tubular member and said member having an extended substantially flat portion with the passage through said member in communication with the valve casing and opening through the extension thereof.

22. In piano player apparatus, a valve

casing having a laterally projecting tubular member and said member having an extended substantially flat portion with the passage through said member in communication with the valve casing and opening through the extension thereof; a pair of plates; an envelope of flexible material to secure said plates in spaced and parallel relation at one side of the extended flat portion of the tubular member for the purpose specified.

23. In piano player apparatus, a valve casing having an exhaust opening arranged to be connected to a vacuum chamber and an opening to the atmosphere; a valve to control the opening and closing of said openings; a tubular projection integral with and extending laterally from said casing having an extended substantially flat portion with the passage in said projection in communication with the valve casing and opening through said extension; a pair of plates, and an envelope of flexible material to attach said plates in spaced parallel relation at one side of the extended portion of the tubular member for the purpose specified.

24. In piano player apparatus, a casing having a valve chamber with a pair of opposed openings and a recessed portion arranged in the casing wall at the outer end of one of said openings; a cap attached to said casing to co-operate with said recess to form a chamber with which one of the casing openings communicates and the other opening in the casing opening to the atmosphere, an exhaust port leading from said latter chamber; a valve to control the opening and closing of the openings from the valve chamber; a tubular member integral with and projecting laterally through the casing with the passage therein in communication with the valve chamber; and a pneumatic at the free end of said member in communication with the passage therein for the purpose specified.

25. In piano player apparatus, a casing having a valve chamber with a recess arranged in the outer wall thereof; a cap attached to the casing to co-operate with said recess to form a chamber; a diaphragm in said latter chamber; a valve opening from the chamber at one side of the diaphragm to the valve chamber; a second opening in the valve chamber opposite to the first opening; an exhaust port from the chamber at the same side as the opening to the valve chamber; a port from the chamber at the opposite side of said diaphragm; a valve in the valve chamber having an operative connection with the diaphragm to be controlled by the latter to control the opening and closing of the openings in the valve chamber.

26. In piano player apparatus, a casing

- having a valve chamber with a recess arranged in the outer wall thereof; a cap attached to the casing to co-operate with said recess to form a chamber; a diaphragm in 5 said latter chamber interposed between the cap and casing; a pair of opposed openings in the valve chamber one leading to the atmosphere and the other to the chamber at one side of the diaphragm; an exhaust port 10 from said latter chamber at one side of the diaphragm and in communication with the opening to the valve chamber adapted to be connected to exhaust means; a second port from the diaphragm chamber at the opposite 15 side of the diaphragm having connection with a tracker tube; a bleeder hole communicating with the ports from the diaphragm chamber at opposite sides of the diaphragm; a valve in the valve chamber having a stem 20 extending through the one opening of the valve casing for operative connection with the diaphragm and adapted to be actuated by the movement of the diaphragm to control the opening and closing of the openings of 25 the valve chamber; a tubular projection extending laterally from and integral with the valve casing and in communication with the valve chamber; and a pneumatic at the free end of said projection in communication 30 therethrough with the valve chamber.
27. In piano player apparatus, a pneumatic, a valve casing, a throat integral with said valve casing and pneumatic, a perforate wall dividing said casing into two chambers 35 one of said chambers having a port opening to the atmosphere, a valve seating in said wall perforation and having a stem to extend through said perforation, a flexible diaphragm in one chamber fitted to said 40 stem, a passage from one chamber at one side of the diaphragm arranged for connection with a tracker tube, an exhaust passage leading from said chamber at the opposite side of the diaphragm, and a bleeder 45 hole communicating with said passages.
28. In piano player apparatus, a chest having a vacuum chamber, control valve casings mounted on the chest in communication with the vacuum chamber in two alined series one at a higher level than the other, operating pneumatics arranged in parallel relation in a single row, members having air 50 passages integral with said valve casing and with the pneumatics, valves in said casings 55 to control the connection of the casing with the vacuum chamber and the openings to the atmosphere, and actuators connected to said pneumatics.
29. In piano player apparatus, a chest having a vacuum chamber therein, control valve casings secured to said chest in communication with the vacuum chamber in longitudinal alinement in two series one at a higher level than the other, operating pneumatics arranged in a parallel alined row laterally 60 of said valve casing, members having air passages between and connecting said pneumatics and the valve casings, said air passages being formed integral with said casings and arranged as a part of said pneumatics, and actuators connected to the pneumatics. 65
30. In piano player apparatus, a vacuum chamber, a pneumatic, a valve casing having a port opening to the atmosphere and a port arranged for connection with the vacuum chamber and a tracker tube, a valve for controlling the opening and closing of said ports to connect the casing with the vacuum chamber and atmosphere, an air passage integral 70 with said casing and arranged to constitute a fixed part of said pneumatic and forming a communication between the casing and pneumatic. 75
31. In piano player apparatus, a pneumatic having a stationary plate and two floating plates with a flexible envelope to connect the floating plates with the stationary plates for movement in parallel relation with the stationary plate, a valve casing; a control valve in said casing, and a tubular communicating throat formed integrally with said valve casing and with said stationary plate of the pneumatic whereby said pneumatic and said valve casing are of unitary 80 construction. 85
32. In piano player apparatus, a pneumatic having a stationary plate, a valve casing; a control valve in said casing; a throat integral with the stationary plate of the pneumatic and with said valve casing, an air passage in said throat communicating with the pneumatic and valve casing, and an attachment flange on said casing. 90
